(57) **CLAIM**

I claim an ornamental design for a scarf, as shown and described.

DESCRIPTION

FIG. 1 is a plan view showing my ornamental design for a scarf;

FIG. 2 is a plan view showing my ornamental design for a scarf, shown with the scarf folded along a first diagonal;
FIG. 3 is a plan view showing my ornamental design for a scarf, shown with the scarf folded along a second diagonal;
FIG. 4 is a front perspective view showing my ornamental design for a scarf, shown as the scarf would be worn by a user; and,

FIG. 5 is a rear perspective view showing my ornamental design for a scarf, shown as the scarf would be worn by a user.

The human figure shown in phantom in FIGS. 4 and 5 is shown for illustrative purposes only, and forms no part of the claimed design. Additionally, FIG. 4 is shown in combination with a scarf ring, also shown in phantom. The scarf ring is shown for illustrative purposes only, and does not form part of the claimed ornamental design.

The scarf is generally made from a fabric having substantially uniform thickness. Therefore, side or edge views would not assist in the understanding of the inventive design.
